UNITED STATES PATENT OFFICE.

HENRY W. SMITH, OF ALLIANCE, OHIO, ASSIGNOR OF ONE-HALF TO FRANK J. RUTH, OF SAME PLACE.

COMBINATION-TOOL.

SPECIFICATION forming part of Letters Patent No. 515,799, dated March 6, 1894.

Application filed May 29, 1893. Serial No. 475,873. (No model.)

To all whom it may concern:

Be it known that I, HENRY W. SMITH, a citizen of the United States, residing at Alliance, in the county of Stark and State of Ohio, have 5 invented certain new and useful Improvements in Combination-Tools; and I do hereby declare the following to be a full, clear, and exact description of the invention, such as will enable others skilled in the art to which 10 it appertains to make and use the same.

My invention relates to combination tools, and has for its object the production of a simple, cheap, and effective implement for shearing and crimping sheet-metal; consisting of 15 a two-part tool integral with which parts are formed a pair of snips or shears for cutting purposes; and also a pair of dies for stamping or crimping purposes, said shears and dies being designed, arranged, and adapted to be 20 used separately, or at one and the same time as will hereinafter appear.

In the accompanying drawings which form part of this specification, and in which like letters indicate like parts wherever employed, 25 Figure 1, represents a side elevation of my invention; Fig. 2, a top plan view thereof; and Figs. 3 and 4 fragmentary sections illustrating face views of the crimping dies.

The invention will now be more fully described and particularly pointed out in the 30 following claims.

Reference being had to the accompanying drawings and letters thereon A indicates one handle of the implement, and B the other, 35 said handles being pivoted together as at C, and terminating in blades D E forming snips or shears as shown by Fig. 1.

Back of the pivotal point C, or on the opposite side from that occupied by the shears 40 D E, are located bosses F. and G formed integral with the handles A, B, respectively and projecting therefrom at an angle. The inner face of boss F is traversed by longitudinal ridges a a, which continue transversely across 45 the handle A; while the boss G and its adjacent handle B are crossed in the same manner by V shaped depressions b b, corresponding with ridges a a, which they are adapted to receive, these parts coacting to form the 50 two members of a crimping die. This being the construction of my invention in its preferred form, its use and operation are too apparent to require much explanation, it being

desirable however, to add: The implement as shown is intended particularly for the use of 55 tinsmiths in the various operations, which they are called upon to perform, of cutting and crimping sheet-metal; and in such use is adapted to cut without crimping, to crimp without cutting, or to cut and crimp simultaneously by one and the same operation of the handles A, B. In the latter important use it will be seen by inspection of Fig. 1, that either the strip or the body of the sheet being operated upon by blades D E, passes immediately between the two members of the crimping die, and is by them formed into a configuration corresponding with their meeting faces, and this without a separate operation or handling of the metal. It is obvious 70 also, that dies of various configurations to meet different requirements of the trade may be employed; or interchangeable dies may conveniently be attached to bosses F, G, for the same purpose; and likewise the crimping 75 and cutting devices may be located on the same side of their common fulcrum C, or on opposite sides from that shown if desired, without in the least departing from the spirit of my invention, which, 80

Having been thus described, what I claim is—

1. A pair of pivoted levers having to one side of their pivotal point shear blades, and to the opposite side a crimping die, the latter crossing said levers transversely and extending to one side thereof, substantially as described.

2. In a cutting and crimping tool, the combination with cutting blades and their pivoted handles, of a pair of dies arranged at an angle to and offset from the plane of the shear blades, substantially as described.

3. In a cutting and crimping tool, the combination with the cutting blades and their pivoted handles, of bosses arranged at an angle to and offset from the plane of the shear blades, and crimping dies formed on the meeting faces of said bosses, substantially as described.

In testimony whereof I subscribe my signature in presence of two witnesses.

HENRY W. SMITH.
